UNITED STATES PATENT OFFICE.

WALTER M. INGRAM, OF SUDBROOK PARK, MARYLAND, ASSIGNOR, BY DIRECT AND MESNE ASSIGNMENTS, TO THE SANITARY TEA BAGGING COMPANY, OF BALTIMORE, MARYLAND, A CORPORATION OF MARYLAND.

BAGGING MACHINE.

Application filed September 19, 1924. Serial No. 738,637.

This invention relates to bagging machines and has for an object to provide a machine for co-acting with an automatic weighing machine, the entire combination of which automatically weighs and bags a commodity in a new and improved manner.

A further object of the invention is to provide a bagging machine which automatically cuts the units of the bag, deposits the commodity therein and sews the bag to a complete closure at a single operation.

A further object of the invention is to provide a bagging machine which will produce a merchandising and culinary bag of material as disclosed in co-pending application Serial No. 734,350 filed August 25, 1924.

A further object of the invention is to provide a bagging machine having a chute for introducing a commodity so arranged as to cut from a strip of fabric a disk, deposit the commodity thereon, cut and place a second disk upon the first mentioned disk and the commodity, and sew the marginal edges of the superposed disks entirely around the perimeter to form a complete commodity bag.

A further object of the invention is to provide improved means for holding the disks which are combined to form a complete bag during the filling and sewing steps of operation of the machine.

A further object of the invention is to provide improved means for holding the commodity in position upon the first disk while the second disk is being cut and superposed thereon.

A further object of the invention is to provide mechanical constructions and movements for operating the device to perform the several functions enumerated.

With these and other objects in view, the invention comprises certain novel parts, elements, units, combinations, constructions, mechanical movements, interactions and functions, as disclosed in the drawings, together with mechanical and functional equivalents thereof as will be hereinafter more fully described and claimed.

In the drawings;

Figure 1 is a view in side elevation of the machine associated with the automatic weighing machine mentioned, certain parts being broken away to show otherwise hidden constructions.

Figure 2 is a view in general vertical diametrical section.

Figure 3 is a top plan view of the bagging turn table taken on line 3-3 of Figure 2.

Figure 4 is a horizontal sectional view through the exhaust mechanism taken on line 4-4 of Figure 2.

Figure 5 is a horizontal sectional view through the feeding and cutting mechanism taken on line 5-5 of Figure 2.

Figure 6 is a top plan view as indicated by lines 6-6 of Figure 2, certain operating parts being broken away.

Figure 7 is a top plan view of the step by step gearing taken on line 7-7 of Figure 2.

Figure 8 is an inverted plan view of the cam as indicated by arrow 8 of Figure 2.

Like characters of reference indicate corresponding parts throughout the several views.

The improved bagging machine which forms the subject matter of this application is adapted to be used in conjunction with a weighing machine which except for certain operating parts forms no part of the present invention, such machine being indicated generally at A, and which forms the subject matter of a co-pending application filed coincidentally herewith.

The bagging machine proper is supported upon a deck 10 which in turn is supported by certain uprights 11, the number and position of such uprights forming no essential limitation of the present invention but arranged and positioned as occasion may make necessary or desirable. The entire structure is supported upon a platform 12 or any other similar supporting means. Above the deck 10, an upright 13 is erected which supports certain parts of the bagging machine and likewise supports the weighing device A.

The bagging machine comprises a turn

table 14 which is provided with a hub 15 and driven by a gear 16 rigidly connected with said hub or formed integral therewith as indicated at Figure 2, such integrality being, however, merely a matter of choice. A gear 16 is in turn operated by a gear 17 which, as will appear more particularly from Figure 7, is provided with teeth throughout one-third of its circumference, the number of teeth being as 1 to 4 to the gear 16. While such arrangement and proportions are found desirable in operation, the invention is not limited to these specific relations and comprises any arrangement for operating the gear 16 with a step by step movement. The gear 17 is operated by a shaft 18 which is driven from any prime mover as the motor indicated conventionally at 19. While the particular gearing for driving this shaft 18 from the motor 19 is unimportant and no limitation upon the invention, it is shown in the drawings as comprising a pinion 20 mounted directly upon the armature shaft 21 and intergeared with a gear 22 carried by a shaft 23. This shaft 23 is intergeared with the shaft 18 in any approved manner as by the worm gearing 24 so that, as the motor 19 is operated, the shaft 18 is rotated continuously and through the medium of the mutilated gear 17 operates the gear 16 intermittently.

Upon the turn table 14 are mounted a plurality of cups 25 which are provided with tubular conduits 26 forming a journal for the free rotation of the cups 25 in the turn table and independent of the rotation of the turn table and communicating with radial tubes 27 which in turn connect with the hub 15. The hub 15 is in communication with a conduit 28 which connects with an exhaust mechanism 29 as shown at Figure 1, so that said conduit 28 is under continuous exhaust. The end of the conduit 28 extends upwardly into the hub 15 and is cut away as indicated at 30 (see Figure 4) so that three of the tubes 27 are under the action of the exhaust, the fourth being free from such exhaust action for the purposes hereinafter mentioned.

The cups 25 are provided about or adjacent to their perimeters with a plurality of upstanding penetrating pins 31. As the turn table 14 carrying the plurality of cups 25 is rotated with a step by step movement in the manner above described, it brings two of the cups 25 under strips 32 of fabric (see Fig. 1) which fabrics are fed from each end by means of points 33 carried upon sprocket chains 34 which in turn operate over sprockets 35 upon the driven shafts 36 and sprockets 37 upon the idler shafts 38. The shafts 36 are driven by means of any convenient gearing indicated conventionally at 39, which as shown embraces a shaft 40 and

worm 41 engaging a worm upon the shaft 42 which is driven intermittently by being connected with the hub 15 as by means of the set screw 43 (see Figure 2). The intermittent drive of the turn table 14, therefore, produces a similar intermittent drive of the sprockets 34 so that, while said turn table is rotating by the operation of the mutilated gears 17, the strips of material 32 are being fed forward a distance to cover the two cups 25. This feeding mechanism is carried upon a plate 44 which forms a bearing for the shaft 42 and is held against rotation in any approved manner as by the brace 45 which extends to and is connected with the upright 13. Above this plate 44 a guide block 46 is located which may be formed integral with the plate 44, as indicated by the section lines at Figure 5, and is held stationary in the same manner by the brace 45, as indicated at Figure 2. This guide block 46 is provided with bosses 47 registering with openings 48 in the plate 44. The guide block 46 and plate 44 are so arranged that the strip of material 32 passes between the block and plate and over the openings 48 beneath the bosses 47. Mounted to reciprocate in the bosses 47 are cutters 49 proportioned to co-act with the margins of the openings 48 to form a shear cut for the fabric 32 located between the block 46 and the plate 44. Preferably, the cutting edge of the cutters 49 are scolloped as at 50 merely for efficiency in operation and for like reason the upper edge is similarly scolloped so that the cutters may be reversed. As shown at Figure 2, the cutters 49 are formed of sheet or similar metal bent to a cylinder with substantially abutting edges as indicated at 51, permitting sufficient resiliency of the cutters to at all times properly fit not only the bosses 47 but the cutting opening 48.

These cutters 49 are operated simultaneously by means of a yoke 52, the ends of which are fulcrumed at 53. The yoke is connected directly with the cutters 49. Such connection in one instance is preferably by means of a ring 54 having ears 55 (see Figure 2) pivoted to the cutter 49 at 56. This forms an opening for the introduction of the commodity through the chute 57 which is the connecting element between the weighing machine A and the bagging machine which forms the subject matter of this application.

The yoke and therewith the cutters are operated by extending the yoke to form a lever 58 from which extends a link 59 which furnishes an oscillating movement to the yoke by any approved type of gearing operating in timed relation therewith. As shown in the drawings, this timing is produced by a cam 60 carried upon and rotating with the shaft 18, the cam groove of which

engages a roller 61 upon the lever 62 connected to the link 63 which in turn connects with the bell crank lever 64 pivoted to the link 59. The groove of the cam 60 is so arranged as to oscillate the cutters in proper timed relation with the operation of the balance of the mechanism as will be hereinafter more fully described.

As the turn table 14 rotates, the disks of fabric located thereon will be brought into position to be operated upon by a sewing machine which is indicated conventionally at 65 in Figure 2, such sewing machine per se forming no part of the present invention and any type of machine capable of performing the operation may be employed in conjunction with the bagging machine forming in its generic embodiment an essential part of the bagging machine but specifically unimportant to the present invention.

In operation, the strips of fabric material are introduced between the plate 44 and the guide block 46 carried by the teeth 33 of the sprocket chains 34 so that they shall cover both of the openings 48 in the plate 44. The relation of the gears 16 and 17 is such that the gear 17 operates the turn table to bring two of the cups 25 under the two cutters 49. In this position both of the cutters descend, operated in the manner hereinbefore mentioned by the actuation of the lever 58 to sever two disks from the fabrics 32 and move them downwardly to be impaled upon the penetrating points 31. One of these fabric disks comes directly in contact with the cup 25 and is subjected to the exhaust as mentioned. This serves to hold the fabric in position while the commodity indicated at Figure 2 is introduced through the chute 57 and through the cutter 49 upon this disk, the exhaust serving also to hold the commodity in position owing to the open weave of the fabric which is preferably of a coarse and very open structure. The cutting of the disk and impaling it upon the penetrating points as indicated at Figure 2, the disks there being given the number 32' for identification, is accomplished simultaneously or approximately instantaneously. The cutters rise and the turn table 14 is rotated a fourth of a revolution by the action of the 1 to 4 gearing 17 upon the gear 16 so that the said commodity disk 32' is now brought under the second cutter and another cup 25 brought under the initial cutter. This action is repeated so far as the initial disk is concerned and at the second cutter a second disk is simultaneously cut and pushed downwardly and likewise impaled upon the points 31, this disk being marked for identification 32" at Figure 2. This cup, the two disks and the contained commodity are still subjected to the action of the exhaust which holds all of the parts properly positioned upon the cup 25 which is

again rotated with the table 14 bringing said first mentioned cup in position to be acted upon by the sewing machine 65. The sewing machine engages the extending perimetrical edges of the two disks 32' and 32", forming a stitching thereabout, such stitching being accomplished by the rotation of the cup 25 and the feed of the sewing machine, no other means for rotating said cup being necessary. The sewing machine is preferably of the type which will form a zigzag or binding stitch over the perimetrical edges of said superposed disks, although as hereinbefore stated the particular type of sewing machine is not essential to the present invention.

At the next step by step movement of the turn table 14 and its several cups, the bag now sewed and completed is removed. While some automatic means may be employed for the purpose, none is here shown and such removal is or may be accomplished manually.

It will be seen that at each stop of the turn table 14 a disk is cut, impaled upon the points 31 upon one cup and the commodity introduced upon said disk, while simultaneously a second disk is cut and superposed upon the previously cut disk and contained commodity and at the same time the sewing machine is operating to close the organized units of a complete commodity bag while at the fourth step the completed bag is being removed. At said fourth position, the bag is no longer subjected to the action of the exhaust, so that it may be easily removed, mechanically or manually.

As all of the parts, elements and mechanical movements which go to make up or contact in the present case are capable of being driven and operating at a very high rate of speed, it is obvious that the device will automatically cut the necessary disks, deposit the necessary commodity and sew the superposed disks at a very great rate of speed.

What I claim to be new is:

1. A bagging machine comprising a turn table, means to rotate the turn table with a step by step movement, a plurality of cups carried by said turn table, a fabric feeder, means to cut disks from the fed fabric and locate them upon said cups, means to introduce a commodity between the positioning of the first and second disks, and means to unite the edges of said superposed disks.

2. A bagging machine comprising a turn table, a plurality of cups carried by said turn table and provided with upstanding penetrating points, a fabric feeder, means to sever disks from the fed fabric and impale them upon said penetrating points upon said cups, means to introduce a commodity between the positioning of the first and second disks on said points, and means to unite the edges of said disks with the commodity contained.

3. A bagging machine comprising a turn table, a plurality of cups mounted to rotate freely upon said turn table and provided with upstanding perimetrical penetrating points, a fabric feeder, means to sever disks from the fed fabric and impale them upon said penetrating points, means to introduce a commodity between the positioning of the first and second disk, and means employing the rotation of the cups for closing the perimetrical edges of said superposed disks.

4. A bagging machine comprising a turn table carrying a plurality of cups mounted and free to rotate thereon, means subjecting said cups to exhaust throughout a portion of the rotation of said turn table, penetrating points upstanding from the perimetrical edges of said cups, a fabric feeder, means to sever disks from the fed fabric and impale them upon said penetrating points, means to introduce a commodity upon one disk preceding the impaling of the second disk thereon, means employing the rotation of the cups for closing the perimetrical edges of said superposed disks, and means to relieve the exhaust from said cups following said closing operation.

5. A bagging machine comprising a turn table having radial arms in communication with an exhaust mechanism, a plurality of cups carried by said turn table in communication with said exhaust arms, penetrating points upstanding about the perimeters of said cups, a fabric feeder, means to actuate the fabric feeder with a step by step movement, cutters positioned to sever disks from the fed fabric and impale them upon the upstanding penetrating points, means to introduce a commodity upon the first impaled disk preceding the impaling of the second disk, means for closing the perimetrical edges of said superposed disks, and means to relieve the exhaust from said cup following said closing operation to facilitate removal of the completed commodity bag.

6. A bagging machine comprising a turn table, an exhaust mechanism, a conduit extending from said exhaust mechanism to said turn table, a plurality of sockets formed adjacent the perimeter of said turn table and in communication with said exhaust conduit, cups mounted to rotate in said sockets and having conduits therein subjected to said exhaust, a fabric feeder, means to actuate the feeder, means to sever a plurality of disks simultaneously from the fed fabric and position them upon a plurality of said cups, means to introduce a commodity upon the first positioned disk before the application of the second disk, means to close the perimetrical edges of said superposed disks, and means to relieve the exhaust from said exhaust mechanism to facilitate removal of the closed bag.

7. A bagging machine comprising a turn table, means to rotate the turn table a pre-determined cycle intermittently, a plurality of cups carried by said turn table corresponding in number to the cycles of operation, a fabric feeder, cutters positioned over some of said cups at their positions of rest, a fabric introduced between the cups and the cutters by said feeder, means to operate the cutters to sever disks from the fabric and position them upon the cups, means to introduce a commodity upon the initial disk preceding the application of the second disk, and means operating in conjunction with one of said cups at its position of rest to close the edges of said superposed disks.

8. A bagging machine comprising a turn table, means to advance the turn table with a step by step movement providing periods of movement and periods of rest, a plurality of cups carried adjacent the perimeter of said turn table, penetrating points upstanding from said cups, a plurality of cutters positioned to co-act with some of said cups at their positions of rest, means to introduce a fabric between the cutters and cups, means to actuate the cutters intermittently to sever disks from the fabric and impale them upon said penetrating points, means to introduce a commodity upon the initial disk preceding the application of the second disk, a sewing machine positioned to engage the perimeters of said superposed disks upon one cup at the position of rest and to rotate the cup to unite said perimetrical edges, and means to advance the fabric intermediate said operations.

9. In a bagging machine, a plate having a plurality of openings, a guide block having openings registering with the openings of said plate, means to introduce a fabric between said plate and said block, a sprocket chain having a plurality of points engaging the margins of the fabric, means to rotate the turn table with a step by step movement, means to advance the sprocket chains to feed the fabric synchronously with the rotation of the turn table, cutters carried by the guide block for severing disks from the fabric, and means carried by the turn table to receive and retain the disks severed by said cutters.

10. In a bagging machine, a turn table, means to advance the turn table and feed a fabric simultaneously and intermittently, cutters positioned to sever sections from the fabric and position them upon the turn table structure, and means to actuate the cutters during the periods of rest of the turn table and fabric.

11. In a bagging machine, an exhaust cup provided with a plurality of impaling points upstanding about its perimeter in spaced relation.

12. In a bagging machine, an exhaust cup having about its perimeter a plurality of upstanding impaling points, and means to move the exhaust cup into and out of operation. exhaust mechanism, a plurality of impaling points upstanding about the perimeter of the cup, and means to move the cup without interrupting the exhaust. In testimony whereof I affix my signature.

13. In a bagging machine, an exhaust mechanism, a cup in communication with the

WALTER M. INGRAM.
